(57) **CLAIM**

I claim the ornamental design for a reciprocating cutting tool, as shown and described.

DESCRIPTION

FIG. 1 is a right-front perspective view of the reciprocating cutting tool showing my new design;

FIG. 2 is a right side elevation view of the reciprocating cutting tool shown in FIG. 1;

FIG. 3 is a left side elevation view of the reciprocating cutting tool shown in FIG. 1;

FIG. 4 is a bottom plan view of the reciprocating cutting tool shown in FIG. 1;

FIG. 5 is a top plan view of the reciprocating cutting tool shown in FIG. 1;

FIG. 6 is a front elevation view of the reciprocating cutting tool shown in FIG. 1;

FIG. 7 is a rear elevation view of the reciprocating cutting tool shown in FIG. 1; and,

FIG. 8 is right-rear perspective view of the reciprocating cutting tool of FIG. 1.
